CLAIM

The ornamental design for a squirrel baffle, as shown and described.

DESCRIPTION

FIG. 1 is a top, front, and right perspective view of a squirrel baffle, showing my new design;

FIG. 2 is a bottom perspective view thereof;

FIG. 3 is a front perspective view thereof;

FIG. 4 is a front elevational view thereof;

FIG. 5 is a rear elevational view thereof;

FIG. 6 is a left elevational view thereof;

FIG. 7 is a right elevational view thereof;

FIG. 8 is a top plan view thereof;

FIG. 9 is a bottom plan view thereof;

FIG. 10 is an enlarged view of portion 10 in FIG. 1;

FIG. 11 is an enlarged view of portion 11 in FIG. 1;

FIG. 12 is an enlarged view of portion 12 in FIG. 2;

FIG. 13 is an enlarged view of portion 13 in FIG. 4;

FIG. 14 is an enlarged view of portion 14 in FIG. 9; and,

FIG. 15 is another perspective view thereof, but shown in an assembled state in an environmental view.

The dash-dash broken lines showing a post in FIG. 15 illustrate environmental structure. All other dash-dash broken lines illustrate portions of the squirrel baffle. The dash-dot-dash broken lines represent the boundaries and indicators of the enlarged views. The broken lines form no part of the claimed design.
